UNITED STATES PATENT OFFICE

DONALD E. WILLARD, OF DANVILLE, ILLINOIS

SUPPORTING MEANS FOR DOORS

Application filed August 15, 1929. Serial No. 386,084.

This invention relates to improvements in supporting means for doors and its purpose is to provide an improved device for supporting the door adapted to travel along a supporting track, such as an airplane hangar door, for example. The principal object of the invention is to provide improved supporting means comprising parts capable of adjustment for varying the spaced relation of the door to the supporting track and for varying the relative positions of the vertical edges of adjacent doors so that they will properly align with each other when in closed positions. A further object of the invention is to provide a supporting device comprising a roller having a vertical spindle connected thereto and journaled in a bearing carried by a bracket attached to the door, in combination with means for adjusting the spindle vertically in its bearing in order to vary the relation of the roller to the door. Still another object of the invention is to provide a roller frame having an upwardly extending spindle journaled in a bracket attached to the door in combination with an adjusting member threadedly engaging the bracket for varying the position of the spindle in its bearing and having a thrust bearing interposed between the adjusting member and the spindle for carrying the weight of the door. Other objects relate to various features of construction and arrangement which will appear more fully hereinafter.

The nature of the invention will be understood from the following specification taken with the accompanying drawing in which one embodiment is illustrated.

In the drawing,

Figure 1 shows a partial elevation of the lower corner of a door with a part of the front cover plate thereof removed to reveal the improved supporting device of the present invention applied to the door and illustrated partially in vertical section; and

Fig. 2 shows a vertical section taken on the line 2-2 of Fig. 1.

As illustrated in the accompanying drawing, the invention is applied to a door 10 comprising a pair of vertical frame members 11 spaced apart and connected by a horizontal

frame member 12, thus providing a chamber 13 located between the inner and outer metal cover plates 14 of the door which are secured to the frame members thereof by suitable means.

In the lower part of the chamber 13, there is located a wheel or roller 15 which is adapted to travel upon a supporting track 16 and which has annular flanges 15^a adapted to extend on opposite sides of the head of the rail which forms the track. In this embodiment, the door is supported at the bottom on a track rail which is secured to or partially imbedded in the floor of the airplane hangar or other building to which the doors are applied. The roller 15 is mounted to rotate upon an axle 17 which is secured in the side frame members 18^a of a roller frame 18. The top transverse portion 18^b of the roller frame is formed integrally with an upwardly extending hollow spindle 20 which is journaled in a bearing hub 21 formed as an integral part of a bracket 22. This bracket is positioned between the frame members 11 in the chamber 13 and is provided with vertically extending flanges 22^a which coact with the vertical faces of the frame members 11 and are secured thereto by means of bolts 23 and nuts 24. The bracket 22 is further provided with upwardly extending arms 22^b which have flat upper ends adapted to coact with the lower face of the horizontal frame member 12 of the door thus providing a support for the weight of the door on the bracket independently of the connecting bolts 23.

The bearing hub 21 is provided with bushings 25 which are secured therein and spaced apart so that their adjacent ends register with the upper and lower extremities of an annular groove 20^a which is formed in the outer peripheral surface of the spindle 20 substantially midway between its upper and lower ends. This annular groove is engaged by a transverse pin 26 which passes through the hub 21 and is secured therein to limit the extent of vertical movement of the spindle within the bearing hub 21 and to maintain these parts normally in assembled relation.

In order to vary the relation of the bottom of the door to the track 16 and to vary the

positions of the vertical edges of the door so that it will properly align with the door casing or with adjacent doors to effect a tight closure, means are provided for adjusting the 5 spindle 20 vertically within the bearing hub 21 and this is accomplished by means of an adjusting member 28 having the form of a bolt provided with a hexagonal head 28^a. The adjusting member 28 threadedly engages 10 an aperture 29 formed in the upper end wall 21^a of the bearing hub and its lower end is provided with a concave surface 28^b adapted to receive the similarly-formed central part of a hard metal washer 30. This washer 15 coacts with the upper part of a spindle ball bearing 31 which is located within a cup-shaped member 32 positioned within the upper enlarged bore 20^b of the spindle. The cup-shaped member 32 serves as a cage for 20 the ball and has a hard metal washer 33 seated in the lower end thereof and provided with an upper concave surface 33^a adapted to coact with the lower portion of the ball 31. The ball thus serves as a thrust bearing 25 between the lower end of the adjusting member 28 and the upper part of the spindle 20 so that the spindle is adapted to rotate freely during the normal movement of the door along a curved track, for example, which requires the pivotal movement of the roller 15 about a vertical axis. When it is desired 30 to vary the relation of the roller 15 to the door, the adjusting member 28 may be manipulated by a wrench to move it vertically 35 in the threaded part 29. This adjusting member retains its adjusting position without the employment of any locking device because the bearing ball 31 permits the free angular movement of the spindle 20 beneath the adjusting member without causing any substantial 40 tendency to effect the turning of the adjusting member.

Although one form of the invention has been shown and described by way of illustration, it will be understood that it may be constructed in various other forms within the scope of the appended claims.

I claim:

1. The combination with a door of a roller 50 adapted to travel on a supporting track, a roller frame in which said roller is rotatably mounted, a spindle extending vertically from said roller frame, a bracket secured to said door and having a bearing hub in which said spindle is journaled, said bearing hub having a threaded aperture at one end, an adjusting bolt threadedly engaging said aperture, a retaining member mounted on said spindle and a spherical ball inserted between 55 said retaining member and the end of said adjusting member for permitting rotation of said spindle and receiving the end-thrust thereof.

2. The combination with a door, of a roller 60 adapted to travel upon a supporting track, a

roller frame in which said roller is rotatably mounted, a spindle extending vertically from said roller frame, a bracket secured to said door and having a bearing hub in which said spindle is rotatably mounted, a cup-shaped member mounted in the upper end of said spindle, a bearing ball mounted in said cup-shaped member, and an adjusting member threadedly engaging said bracket and having a part engaging the upper side of said ball for receiving the end-thrust transmitted thereto from said spindle.

3. The combination with a door having a pair of vertical frame members spaced apart and connected by a horizontal frame member, of a roller mounted between said vertical frame members and adapted to travel upon a supporting track, a roller frame in which said roller is rotatably mounted, a spindle extending vertically from said roller frame, a bracket having said spindle journaled therein, said bracket having flanges secured to said vertical frame members, and arms extending upwardly from said bracket and engaging the under side of said horizontal frame member.

4. The combination with a door, of a roller adapted to travel upon a supporting track, a roller frame in which said roller is rotatably mounted, a spindle extending vertically from said roller frame, a bracket secured to said door and having a bearing in which said spindle is journaled, said spindle having a cylindrical recess in the upper end thereof, a cup-shaped member seated in said recess, a single ball bearing mounted in said cup-shaped member, and an adjusting member threadedly engaging the upper portion of said bracket and coacting with said ball bearing for adjusting said spindle vertically in said bracket.

5. The combination with a door, of a roller adapted to travel upon a supporting track, a roller frame in which said roller is rotatably mounted, a spindle extending vertically on said roller frame, a bracket secured to said door and having a sleeve in which said spindle is journaled, said sleeve having a closed upper end provided with a threaded aperture, an adjusting member threadedly engaging said aperture for exerting an end thrust on said spindle to vary its position within said sleeve, and ball bearing means carried by the upper end of said spindle to receive the end thrust of said adjusting member.

In testimony whereof, I have subscribed my name.

DONALD E. WILLARD.
